US00D861573S

(12) **United States Design Patent** (10) Patent No.: **US D861,573 S**
He et al. (45) Date of Patent: ** Oct. 1, 2019

(54) **AERIAL VEHICLE**(71) Applicant: **SZ DJI Technology Co., Ltd.**,
Shenzhen (CN)(72) Inventors: **Baichuan He**, Shenzhen (CN); **Yumian Deng**, Shenzhen (CN); **Wenbo Li**, Shenzhen (CN)(73) Assignee: **SZ DJI Technology Co., Ltd.**,
Shenzhen (CN)(**) Term: **15 Years**(21) Appl. No.: **29/634,272**(22) Filed: **Jan. 19, 2018**(51) LOC (12) Cl. **12-07**

(52) U.S. Cl.

CLAIM

The ornamental design for an aerial vehicle, as shown and described.

DESCRIPTION

FIG. 1 is a top front perspective view of an aerial vehicle showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the aerial vehicle that form no part of the claimed design.

1 Claim, 6 Drawing Sheets
